UNITED STATES PATENT OFFICE.

JOHN A. BARTOSZEWCZ AND PAUL P. BARTOSZEWCZ, OF CHICAGO,
ILLINOIS.

PASSE-PARTOUT.

SPECIFICATION forming part of Letters Patent No. 577,676, dated February 23, 1897.

Application filed April 13, 1896. Serial No. 587,296. (No model.)

To all whom it may concern:

Be it known that we, JOHN A. BARTOSZEWCZ and PAUL P. BARTOSZEWCZ, citizens of the United States, residing at Chicago, in the county of Cook and State of Illinois, have invented certain new and useful Improvements in Passe-Partouts, of which the following is a specification.

This invention relates to improvements in that class of light picture-frames known as "passe-partouts;" and it consists in certain peculiarities of the construction, novel arrangement, and operation of the various parts thereof, as will be hereinafter more fully set forth and specifically claimed.

The objects of our invention are, first, to provide a passe-partout which shall be simple and inexpensive in construction yet neat and attractive in appearance, and, second, such a passe-partout by reason of the peculiar construction of which the mat or frame to be interposed between the picture and glass may be readily removed or inserted without the removal or displacement of the back of the frame.

In order to enable others skilled in the art to which our invention pertains to make and use the same, we will now proceed to describe it, referring to the accompanying drawings, in which—

Figure 1 is a rear perspective view of our passe-partout. Fig. 2 is a rear view in elevation thereof. Fig. 3 is a rear view in elevation, showing the mat partly withdrawn from the frame and the sliding cover of the back removed. Fig. 4 is a face view in elevation, showing the mat partly withdrawn from the frame; and Fig. 5 is an enlarged cross-sectional view taken on line 5 of Fig. 5.

Similar letters refer to like parts throughout the different views of the drawings.

A represents the glass, which may be made of any suitable size and form, but preferably rectangular, as shown in the drawings. On the rear surface of the glass and along three sides of the perimeter thereof is placed a strip or strips a, of a thickness somewhat greater

than the mat B. On the rear surface of the strips a is placed a board or back C, which may be reinforced by an additional board or 50 back C', secured to its rear surface. The board C is provided with a central opening c for the reception of a photograph or picture, and the board C' is formed with a like opening c', which is slightly tapering toward its 55 upper end and is open at its lower portion to receive the sliding cover D, which is provided with a hinged support d to hold the frame in an inclined position, as shown in Fig. 1 of the drawings.

As is clearly seen in Fig. 5, the opening c' in the board C' is formed with angular edges to receive the correspondingly-shaped edges of the cover D, which is adapted to be inserted in said opening or removed therefrom 65 when it is desired to place the picture in the opening c and against the mat B, which is provided with an opening b for the exposure of the photograph or picture. The board C, strip or strips a, and glass A are secured together by means of suitable strips of material e, secured on their edges, as is clearly shown in the different views of the drawings. The strips e extend inwardly on the face of the glass A beyond the inner surface of the 70 pieces a, thus concealing the crevice between said pieces and the edges of the mat.

While we have shown the frame open at its bottom to allow of the insertion or withdrawal of the mat, yet we may construct the 80 frame so that the open space thereof may be located at the sides or top, as may be desired.

By employing our invention it is apparent that the mat B may be covered with cloth b' or other material, upon which ornamental designs may be embroidered or embellished, and may be inserted or removed from the frame at pleasure and without displacing the picture or removing the back.

Having thus fully described our invention, 90 what we claim as new, and desire to secure by Letters Patent, is—

As an improved article of manufacture, a passe-partout, consisting of the glass A, the

pieces or strips *a*, secured to its rear surface at three sides of its perimeter, a board or back *C*, having the central opening *c*, secured on the rear surface of the strips *a*, the reinforcing board or back *C'*, having the opening *c'*, the sliding cover *D*, provided with the hinged support *d*, and adapted to fit in the opening *c'*, and the securing-strips *e*, uniting the edges of the glass *A*, strips *a*, and back *C*, substantially as described.

JOHN A. BARTOSZEWCZ.
PAUL P. BARTOSZEWCZ.
